OR 0 837

Hudson & Bridges' Design for a Cooking Stove.
Patented Oct. 7, 1836.

Fig. 1.

Fig. 2.

Dec. 837

Hudson E. Bridge, of St. Louis, Mo.
Letters Patent No. 837. Dated October 7, 1856.

The Schedule referred to in these Letters Patent and making part of the same.

To all whom it may concern:

Be it known that I, Hudson E. Bridge, of the City and County of St. Louis, and State of Missouri, have invented or produced a new and original ornamental Design for looking stoves; and I do hereby declare that the following is a full and exact description thereof, reference being had to the accompanying drawings, making part of this specification.

Fig. 1, being a perspective view of the stove.

Fig. 2, a view of one of the side plates, including the oven doors thereof.

Fig. 3, a view of the front plate above the hearth, including the two front fire-place doors thereof.

Like letters designate corresponding parts in all the figures.

The doors, on which the principal ornaments are located, are surrounded with borders A, each composed of three mouldings, a, b, c. rising one above another. The corners, H, of the stove, are rounded and engrailed, or croft-fluted, as shown. The center of the large oven door is adorned with an escutcheon, representing a bearded face in the center, and bordered with an irregular scroll-edge L, all in relief. A shaft L passes vertically through the escutcheon, having a slot and moulding at the upper end, and a trefoil at the lower end.

A horizontal shaft T, adorned with trefoils at the ends, passes through the center of the escutcheon, and supports censers P, P, at the sides thereof. At the top and the bottom of the door panel, are scrolls L, L, and at the upper corners, other scrolls M, M, pierced with wands

Dec. 837

12. n. Other scrolls j. q. are situated near the bottom of the panel, pierced by a shaft o., with a leaf extremity. The ornament is fringed with a waved fillet s., or with a raised margin. All the ornaments are in relief.

Each of the other doors has an amulet B. in the center, with flanches c. d., at the top, bottom, and sides. The small oven door has scrolls e. f., at the top and bottom, and whirls g. g., pierced with shafts g. g., adorned with trifolts at the sides; all being united at the corners with curved margins, as seen in Fig. 2. The fire-place doors have whirls j. j. surrounding the central amulet, as shown in Fig. 3. Small panels F. F. at the sides of the front fire-place doors, are adorned in the center with ornaments G. G. as shown in Fig. 3.

Another panel, below the hearth, has a similar ornament I. as shown in Fig. 1. The legs M. M. (Fig. 1), are adorned with similar ornaments. All the ornaments are in relief.

What I claim, and desire to secure by Letters Patent, is the ornamental configuration, composing a design for a cooking stove, substantially as represented and specified.

The above specification of a new original design for a stove, signed by me this twenty-ninth day of August, 1856.
